UNITED STATES PATENT OFFICE.

JOHN C. SCHELLENG, OF EAST ORANGE, NEW JERSEY, ASSIGNOR TO WESTERN ELECTRIC COMPANY, INCORPORATED, OF NEW YORK, N. Y., A CORPORATION OF NEW YORK.

SPACE DISCHARGE SYSTEM.

Application filed March 20, 1924. Serial No. 700,554.

This invention relates to systems of space discharge devices and more particularly to a method of and means for providing an arrangement whereby separate units including 5 three electrode devices of this type may be connected in parallel relation to each other with respect to external circuits.

An important object is to couple independent units, comprising space discharge devices, in parallel relation to each other with respect to an external circuit so that the production of spurious oscillations in the system is prevented.

A feature of this invention is the provision 15 of reactive means included in a circuit common to separate space discharge units for connecting them in parallel to each other with respect to an external circuit so that inter-unit "singing" does not occur.

20 When considerable numbers of space discharge devices are to be connected in parallel relation, it often becomes necessary, as a matter of constructional convenience or for other reasons, to locate one bank on a panel a little 25 removed from one or more other banks and to connect the several banks in parallel relation. A phenomenon which may be described as interbank singing then often occurs. In the limiting case each bank may consist of a 30 single device, but the utility of this invention and its applicability in practice relate principally to the case where each bank of tubes 35 consists of a considerable number i. e. ten in a specific case.

35 A general object of the invention is, therefore, to reduce interbank singing or the production of free oscillations. These oscillations are especially undesirable in cases where the system is to be used for faithfully reproducing waves of a selected frequency or frequency band impressed on the input circuit 40 of the system, as in carrier wave signaling. The free oscillations may cause interruptions to service by producing serious overloads or 45 abnormally high potentials, and the latter may endanger the apparatus.

Among other disadvantages, the production of free oscillations often prevents the system from operating at the desired frequency, 50 causes distortion of the wave form to be repeated, wastes energy by diverting it from a useful purpose, thereby reducing the efficiency of the system, and may cause serious over-heating of the circuit conductors and

lead-in wires of the electrodes of the discharge 55 devices, whereby the devices are liable to be destroyed.

The production of free oscillations in a system of the type described above is in general due to the cyclic transfer of energy from the 60 anode circuit of the system to the grid circuit, the amplitude and phase of the resulting grid potentials, relatively to the corresponding anode potentials, being such as to set up and maintain a current flow in the system. The 65 frequency of the free oscillations is determined by the inherent reactances of the system. The inherent reactances of a system of this kind may be defined as the grid-filament, 70 grid-plate and filament-plate capacities of the discharge devices, the capacities of these elements to earth and to other apparatus, together with the inductances and capacities of the conductors interconnecting the devices, and those connecting them with the associated 75 input and output apparatus.

The present invention provides a reactive device, adapted to be included in the circuit connecting the separate space discharge units, for eliminating the tendency to produce un- 80 desired oscillations in the system.

In accordance with this invention a reactive device, comprising an inductance having a resistance connected in parallel thereto, has its terminals connected to the common conductors or bus-bars for the corresponding electrodes of the discharge devices of the different units and has an intermediate point of the elements of the reactive device connected 85 together and to the common circuit connecting the input or output apparatus to the space discharge system.

The novel features and combinations which are believed to be characteristic of the invention will be set forth with particularity in 90 the appended claims. The invention itself, however, as to both its organization and method of operation will best be understood by reference to the following description taken in conjunction with the attached drawings in 95 which,

Fig. 1 illustrates a radio transmitting system including the invention as applied to the grid circuit of two banks of tubes, and

Fig. 2 illustrates a similar system in which 100 the reactive device constituting the invention is applied to the plate or anode circuit of a two bank set.

Referring now to Fig. 1 there are shown two units 1 and 2 each comprising a plurality of parallel connected space discharge amplifiers 3.

5 The impedance control electrodes of the tubes 3 of each group are connected to a common bus-bar 4. The bus-bars are connected together by a circuit including the device 5 which comprises parallel connected inductance 6 and resistance 7.

10 A source 8 supplies high frequency waves through the transformer 9 and lead 10 to the intermediate point of the parallel connected reactive device 5.

15 The coil 6 should be so wound that the two sections are inductively coupled and their inductances are additive, as viewed from bank to bank. The co-efficient of mutual inductance for the two portions of coil 6 should be

20 as high as possible, since the higher the mutual inductance the lower the impedance of coil 6 for the waves to be amplified.

25 A resistance 11 is connected in shunt to the secondary winding of the transformer 9, one terminal of which is connected to ground at 12. The resistance 11 is of such magnitude relatively to the internal impedance of the discharge devices, that they operate to repeat faithfully the high frequency waves without distortion.

30 The source 13 supplies, through a filter 14, a polarizing potential to the impedance control electrodes of the amplifiers 3. The filter 14 functions to suppress voltage variations of the source 13, whereby a constant potential is impressed upon the control electrodes of the amplifiers 3.

35 An alternating current source 15 supplies heating current to the filaments of the amplifiers 3 through transformers 16.

40 The secondary windings of each transformer 16 is connected in parallel with two condensers. The mid-point of the transformer secondary and the lead connecting the adjacent plates of the condensers are connected together and to ground 17 by the lead 18. Obviously a single transformer 16 could be used to supply heating current to the filaments of both banks of amplifiers.

45 The condensers serve as shunt paths of low impedance, about the transformer secondary, for the high frequency waves supplied by the source 8.

50 The input circuit of the amplifiers extends from ground 12 through the parallel connected secondary winding of the transformer 9 and resistance 11, conductor 10, intermediate point of the device 5 to the bus-bars 4, control electrodes of the devices 3 of groups 1 and 2, their cathodes, condensers shunting the secondaries of transformer 16, leads 18 to ground 17 and thence back to ground at 12.

55 Space current is supplied by the source 19 to the two groups of amplifiers connected in parallel with respect thereto, through the

choke coil 20 and lead 21 to the bus-bars 22 common to the amplifiers of each group. A blocking condenser 23 prevents direct current from flowing through the transformer 24.

70 The space current path of the amplifiers may be traced as follows. From the positive terminal of the source 19, choke coil 20, plates of the discharged devices included in groups 1 and 2, their cathodes, the secondaries of the 75 transformers 16, leads 18 to ground at 17 and back through ground to the negative terminal of the source 19.

75 Amplified high frequency waves produced in the output circuits of the amplifiers are supplied through the blocking condenser 23 to the tuned circuit comprising the primary winding of the transformer 24 and condenser 25 connected in parallel thereto.

80 The choke coil 20 serves to prevent the flow of high frequency waves to ground through the source 19 and the transformer 24 supplies the amplified waves to the antenna 26.

85 Where the separate units are connected to input and output apparatuses by common connections, undesired oscillatory waves, flowing through the circuit formed thereby, may be fed back to the control element through any coupling interconnecting them, as for example, through the interelectrode 90 capacities within the devices. Conditions may be such that sustained oscillations will be produced in the circuits of the system.

95 Referring to the statement above describing the input circuit of the amplifier system, it will be seen that the high frequency voltage waves produced in secondary of transformer 9 by the source 8 are transmitted through the conductor 10 to the intermediate point of the inductance 6 and are effective 100 through parallel paths. Each path extends from one terminal of the secondary winding of the transformer 9, through one portion of the coil 6 in parallel with one portion of resistance 7, the space path between the control 105 electrodes and cathodes of the amplifiers of groups 1 or 2, condensers shunting the secondary winding of transformers 16, ground 17 of group 1 or 2 to ground at 12 and thence to the other terminal of the secondary winding of 9.

110 Undesired oscillatory impulses may be fed back through the interelectrode capacities of the amplifiers and hence tend to flow from one bus bar 4 to the other bus bar 4 through the 115 reactive device 5.

120 By designing the coils 6 so that the impedance thus inserted in lead 10 for currents of the frequency to be amplified is small, while that of the whole coil is high for the 125 undesired oscillatory impulses, and using a shunting resistance adapted to impose a high damping effect for high frequency currents, the undesired impulses will in part be prevented from traversing the coil 6 and hence 130

will in part be diverted to the shunt path including the resistance 7, by which they will be suppressed or dissipated.

In Fig. 2 there is shown a radio transmitting system, which is similar to that illustrated in Fig. 1, in which like parts are identified by like reference characters.

The circuit of Fig. 2 differs from that shown in Fig. 1 as follows, a polarizing potential is impressed upon the control electrodes of the amplifiers 3 of the two units by a battery 27 directly connected between the resistance 11 and ground 12, and the reactive device 5 is included in the common output connection for the amplifier units 1 and 2.

In this case the amplified energy is supplied from the units 1 and 2 through the two portions of the coil 6 in parallel, while spurious oscillations are impressed upon a path connected to the terminals of the reactor 5. The design of the reactor 5 is similar to that described above. The two sections of the inductance 6 and its shunting resistance 7 are in series for currents circulating between the two units and hence these impulses will be diverted in part by the coil 6 to the resistance 7, by which they will be suppressed or dissipated.

While in the preceding description the amplifier units or banks 1 and 2 are shown as consisting of three parallel connected discharge devices 3, it is to be understood that the principles of this invention may be applied to a system having any number of discharge devices, one or more in each unit, and may be used with banks or units each having a different number of discharge devices, whether adapted to operate at high or low power.

40 Where an equal number of discharge devices are included in each bank or unit the input or output apparatus should be connected to the mid-point of the reactive device.

45 When the number of discharge devices included in the units is unequal, the input or output apparatus should be connected to the reactive device so that the impedance of the sections of the reactive device, for waves of 50 the frequency to be repeated, between the point of connection and the respective units is inversely proportional to the number of discharge devices in the units.

Thus, if the first unit includes N_1 discharge devices and the other units N_2 discharge devices, the connecting point for the input or output apparatus, should be such that

$$\frac{L_1 + M}{L_2 + M} = \frac{R_1}{R_2} = \frac{N_2}{N_1},$$

60 where L_1 represents the self-inductance of the inductance coil section between the first unit and the connecting point and similarly L_2 represents the self-inductance of the coil section between the connecting point and the

second unit, M represents the mutual inductance between the coil sections, R_1 represents the impedance of the parallel connected resistance section between the first unit and the connecting point and similarly R_2 represents the impedance of the resistance section between the connecting point and the second unit.

If desired the input and output arrangements of the invention, as disclosed with reference to Fig. 1 and 2 respectively, may be jointly used in a single circuit.

This method of preventing interunit "singing" has been applied with good effect to a radio telephone system employing two banks, including ten discharge devices each adapted to respectively deliver approximately 10 kilowatts at about 60,000 cycles through its output circuit. Space current was supplied to the anodes of the discharge devices at about 10,000 volts.

In the arrangement just described the individual tubes of each bank were provided with additional means, not herein described, adapted to prevent "singing" because of the coupling effects between the input and output circuits of discharge devices included therein. Each bank as a whole may also be provided with any suitable means to prevent intertube "singing" between the tubes of the bank without interfering with the functioning of the elements of the present invention.

The reactive device in this case consisted of a coil approximately 3 inches in diameter, 2 inches long, having 22 turns per inch and its inductance was .125 millihenry and a resistance of 600 ohms connected in parallel to the coil.

This invention may be used with any even number of pairs of banks, i. e. 4, 8, 16, etc., by connecting each pair as hereinbefore described through a reactive device, the pairs in a similar manner through additional reactive devices and finally the interconnecting conductor for the groups of banks through a reactive device to a single conductor for connecting them to either the input or output apparatus.

Again it is to be understood that this invention is not to be limited to specific details described above, but only by the scope of the attached claims.

What is claimed is:

1. In a space discharge system comprising a plurality of parallel connected units each unit comprising a bank of space discharge devices, the method of preventing interbank singing in the system which comprises impressing undesired oscillations upon a path of high impedance connecting said banks, and transmitting oscillations of desired frequencies through a part of said path which is of low impedance therefor.

2. A space discharge system comprising a plurality of units each including three-elec-

trode space discharge devices, an external circuit, and means for connecting said units in parallel with respect to said circuit comprising a reactance element having its terminals connected to said units and an intermediate point thereof connected to said circuit.

3. A space discharge system comprising a plurality of units each including three-electrode space discharge devices, an external circuit, and means for connecting said units in parallel with respect to said circuit comprising a reactance element having its terminals connected to said units and at least a portion of said element connected between each unit and said circuit.

4. A space discharge system including a plurality of units each including at least one three-electrode space discharge device, an external circuit, and means for connecting said units in parallel with respect to said circuit comprising a reactance element having its terminals connected to corresponding electrodes of the device included in said units and an intermediate point connected to said circuit.

5. A space discharge system comprising a plurality of units each including at least one three-electrode space discharge device, means for causing said units to operate simultaneously, comprising a reactor, the corresponding electrode of the device included in each unit being connected by a conductor to a terminal of said reactor, a portion of said reactor being connected between each unit and a circuit external to said units.

6. A space discharge system comprising a plurality of units parallel connected, relatively to an external circuit, by means comprising a path of high impedance for undesired oscillations in series between said units and a path of low impedance for desired oscillations between each of said units and said circuit.

7. In a space discharge system including a plurality of parallel connected space discharge units, the method of preventing the production of undesired oscillations in the system which comprises causing oscillations of desired frequencies from the respective units to traverse parallel conducting paths therefor, and impressing oscillations of undesired frequencies upon a path, including in series portions of said parallel paths, to control the suppression of said undesired oscillations.

8. In a space discharge system including a plurality of parallel connected space discharge units, the method of preventing the production of undesired oscillations in the system which comprises causing oscillations of desired frequencies from the respective units to traverse parallel conductive paths therefor, and impressing oscillations of undesired frequencies upon a path including in series portions of said parallel paths whereby said

undesired oscillations are diverted to a conductive suppression path associated with the said series portions.

9. A space discharge system comprising a plurality of units each including three-electrode space discharge devices, means for causing said units to operate simultaneously, and a reactance element having its terminals connected to the corresponding electrodes of said units and its mid point connected to a circuit external to said units.

10. A space discharge system comprising a plurality of units each including three-electrode space discharge devices, a reactance device comprising an inductance and resistance connected in parallel having its terminals connected to the corresponding electrodes of said units and its mid point connected to an external circuit.

11. A space discharge system comprising a plurality of units each including three-electrode space discharge devices having their corresponding electrodes connected to a common conductor, an external circuit, and means for connecting said units in parallel with respect to said circuit comprising a reactor having its terminals connected to said common conductors and its midpoint connected to said circuit.

12. A space discharge system comprising a plurality of units each including three-electrode space discharge devices having their corresponding electrodes connected to a common conductor, a reactor consisting of parallel connected inductance and resistance having its terminals connected to said common conductors of said units and its midpoint connected to an external circuit.

13. In a vacuum tube system a group of tubes in parallel, a connection between corresponding electrodes thereof, a second group of tubes in parallel, a connection between like corresponding electrodes thereof, a connection between said first-named connections including an inductance shunted by a resistance, and a circuit extending from an intermediate point on said inductance and resistance to the cathodes of said tubes.

14. In a space discharge system, a first group of discharge devices connected in parallel, a connection between corresponding electrodes thereof; a second group of discharge devices connected in parallel, a connection between corresponding electrodes thereof; a conductive path extending between said first and said second connections including a reactive device, an external circuit connected at a point on said reactive device such that the impedance of the reactive device between said external circuit connecting point and the connectors for the respective groups is inversely proportional to the number of discharge devices in the respective groups.

15. In a space discharge system a unit com-

prising N_1 discharge devices having corresponding electrodes connected in parallel, a second unit comprising N_2 discharge devices having corresponding electrodes connected in parallel, an apparatus external to said units, a conductive path connecting the first unit to said apparatus including an inductance L_1 and a resistance R_1 in parallel, a conductive path connecting the second unit to said apparatus including an inductance L_2 and a resistance R_2 in parallel, mutual inductance M between L_1 and L_2 , the values of said inductances and said resistances being such that

$$15 \quad \frac{R_1}{R_2} = \frac{L_1 + M}{L_2 + M} = \frac{N_2}{N_1}.$$

16. In a system comprising two physically separate banks, each bank comprising a plu-

rality of parallel connected space discharge devices, means for causing simultaneous operation of said units, and means for preventing singing comprising an interbank reactor including an inductance, connecting the entire group of parallel connected electrodes of one unit with the corresponding group of parallel connected electrodes of the other unit.

17. In a combination in accordance with claim 16, a resistance in shunt to the said inductance and constituting an element of said reactor and a lead extending from an intermediate point of said reactor to external apparatus.

In witness whereof, I hereunto subscribe my name this 19th day of March, A. D., 1924.

JOHN C. SCHELLENG.
